UNITED STATES PATENT OFFICE

CHARLES ALGERNON PARSONS, STANLEY SMITH COOK, AND LOUIS MORTIMER DOUGLAS, OF HEATON WORKS, NEWCASTLE-ON-TYNE, ENGLAND; SAID COOK AND DOUGLAS ASSIGNEES TO SAID PARSONS; KATHARINE PARSONS, VINCENT THOMPSON, AND FREDERICK GORDON HAY BEDFORD LEGAL REPRESENTATIVES OF SAID CHARLES ALGERNON PARSONS, DECEASED

STEAM TURBINE AND VALVES THEREFOR

Application filed May 31, 1929, Serial No. 367,191, and in Great Britain June 28, 1928.

The invention relates particularly to valves for controlling the flow of elastic fluid but, while certain features of the invention are of general applicability, our improved valve 5 is especially designed for controlling the flow of steam in marine turbine installations having ahead and astern turbines and the invention consists in part of combinations in such an installation.

10 In such installations, it has been found in practice that when running ahead, steam is liable to leak past the relative controlling valve into the astern turbine which is being rotated by the ahead turbine in a direction 15 opposite to its working direction under which condition heat is generated and in view of this fact and also of the fact that the leakage steam is initially at a temperature substantially 20 equal to the maximum temperature of the boiler or superheater a high temperature may be reached and damage may be caused to the astern turbine blades.

The main object of the present invention is 25 to avoid the above difficulty. This result is secured by combining with the astern turbine of such an installation our improved valve, which valve also may be used in other combinations where it is important to prevent the passage of leakage elastic fluid.

With such an object, the invention consists 30 in the combination of elements hereinafter described and particularly pointed out in the claims.

Referring to the accompanying drawings, 35 which show one constructional form of the invention by way of example,

Figure 1 is a sectional elevation through the valve as a whole,

40 Figure 2 being as regards its upper half a cross-section on the line A—A and as regards its lower half a cross-section on the line B—B of Figure 1;

Figure 3 shows a developed view of the 45 main steam ports;

Figures 4 and 5 show in cross-sectional elevation modified forms of certain details of the leak-off valve and adjuncts.

Figure 6 is a diagrammatic sectional elevation of a marine turbine installation with 50 my improved valve.

In carrying the invention into effect according to the form shown in Figures 1 to 3 and 6, the valve proper, *a*, *b*, is of the double-beat type enclosed in a suitable casing, *c*, with inlet, *c*¹, its spindle, *d*, passing through the usual cover, *e*, provided with gland, *f*, and bridge, *g*.

In the particular example of the invention under description, it is assumed that the spindle is vertical and that the double-beat valves close in the upward direction.

When open, steam passes through the upper valve, *a*, direct and through the lower valve, *b*, by way of the usual surrounding duct, *h*, to an additional valve chamber, *i*, formed as an upward extension of the valve casing and preferably integral therewith. This additional chamber has the general form of a cylinder co-axial with the spindle *d*, of the double-beat valve and its lower part is surrounded by an annular duct, *k*, connected on the one hand by way of the outlet, *m*, to the condenser or elsewhere and on the other hand by way of a suitable port, *n*, (or suitable ports) to the interior of the chamber, the function of these parts being to lead off any steam that may leak past the double-beat valve.

The upper part of the chamber is surrounded by a second annular duct, *o*, which increases in area towards its outlet, *r*, partly enveloping the annular duct, *k*, and is connected to the interior of the chamber, *i*, by ports, *s*, and bridges *s*¹ (see Figure 3). A piston valve, *t*, the operative part of which consists of a ring, *t*¹, attached by radial webs, *t*², *t*³, to the boss, *t*³, is mounted on an upward extension of the main valve spindle, *d*, in the additional valve chamber, *i*.

The spacing of the ports, *n* and *s*, the dimensions of the piston valve, *t*, and so forth are so chosen that when the double-beat valve is closed the ports, *s*, to the main outlet, *r*, are covered by the piston valve, *t*, while the leakage port *n* is open, so that any steam passing the double-beat valve is led off direct to the condenser or elsewhere through the outlet, *m*. When, however, the double-beat valve is opened, the same manipulative movement causes the piston valve, *t*, to descend,

closing the leakage port, *n*, and at the same time by its continued movement opening the ports, *s*, to the main outlet.

In order to minimize leakage of steam during the initial part of this opening movement before the leakage port is closed, the mitres on the two elements, *a*, *b*, of the double-beat valve may be provided with upwardly-projecting skirts, *a*¹, *b*¹, serving as pistons in relation to their respective seatings, *a*², *b*².

The piston valve, *t*, may be either of a simple cylindrical form without packing (see Figure 1) working directly in contact with corresponding walls of the valve chamber, *i*, or a liner, *u*, (see Figure 4) with ports, *u*¹, and bridges, *u*², may be fitted and the piston valve provided with ramsbottom rings, *t*⁴; or alternatively packing rings, *v*, (see Figure 5) preferably in conjunction with leaf or garter springs to press them against the piston valve, *t*, may be arranged in the chamber wall.

Whatever the form of piston valve and packing adopted, if desired the upper edge of the piston valve, *t*, may be provided with a narrow cylindrical edge or lip, *t*⁵, (see Figure 5) adapted to come in contact with a flexible annular disc, *w*, secured to the valve casing, *c*, so that seating of the piston valve is effective notwithstanding differential expansion due to temperature and so forth.

Suitable external indicating means, such as the indicator, *x*, (see Figure 1) pinned to the valve spindle, *d*, may be provided to show the position of the valve, such means preferably indicating the completely shut-off position and also the position when the valve first opens to the outlet branch.

In Figure 6, there is shown a marine turbine installation of the preferred form, embodying the invention, in which *A* is a casing enclosing the ahead and astern turbines 10, 11, having the respective steam inlets 12, 13, these ahead and astern turbines having the common condenser passage 14 and condenser

15. Steam is admitted to the astern turbine inlet 13 through pipe 16 under the control of the valve above described, the leak-off port *n* of the valve being connected by pipe 17 to the condensing passage 14 of the condenser.

50 It will be understood that the leak-off valve may be combined with other types of combined ahead and astern turbine installations.

Although the invention has been described by way of example with a valve of the double-beat type, it will be understood that it is equally applicable with valves of many other types whether hand or power operated. In addition the details of construction and relative arrangements of the component parts of the valve structure may take forms other than those described above without exceeding the scope of the invention.

What is claimed is:

1. An elastic fluid-controlling device comprising in combination, a valve casing having

inlet and main and leak-off outlet ducts and disposed within said casing an inlet valve controlling said inlet duct and also disposed within said casing a common valve controlling said main and leak-off ducts, said common valve being of the hollow piston type with imperforate walls and performing its dual function by virtue of different operative edges; positively-associated lengths of spindle on which said valves are mounted in such relation thereto and to said ducts that when said inlet and said outlet valves are both closed, said leak-off valve is open.

2. An elastic fluid-controlling device as claimed in claim 1, in which said valves are mounted on a common spindle, said leak-off duct being controlled by one operative edge of said piston valve and being disposed axially of said spindle between said inlet duct and said outlet duct controlled by the other operative edge of said piston valve.

3. An elastic fluid-controlling device as claimed in claim 1, in which said inlet valve is of the double-beat type, each beat to ensure tightness being provided with a piston skirt.

4. The combination with the ahead and astern turbines of a marine turbine installation, of a valve device controlling the steam admission of the astern turbine and comprising a valve casing having inlet and main outlet and leak-off ducts and interconnected valves controlling said ducts and arranged so that when the inlet is closed the main outlet duct is closed but the leak-off duct is open, while when the inlet is open, the main outlet duct is open but the leak-off outlet duct is closed, substantially as and for the purpose described.

In testimony whereof we have signed our names to this specification.

CHARLES ALGERNON PARSONS.

STANLEY SMITH COOK.

LOUIS MORTIMER DOUGLAS.
